MECHANISM FOR USE IN THE MANUFACTURE OF ARTIFICIAL SILK

Peter P. Kriek, Enka, N. C., assignor to American Enka Corporation, Enka, N. C., a corporation of Delaware

Application July 13, 1938, Serial No. 219,081

5 Claims. (Cl. 18—8)

This invention relates to power transmitting mechanisms in which the speed of operation of the driven means may be varied a small degree with precision, and more particularly the invention relates to means for spinning artificial silk comprising a differential gearing having included therein transmission mechanism such as epicyclic transmission for driving godets at controlled speeds and for effecting small percentage speed variations in the travel of the filaments being spun during the relatively long period involved in a complete spinning operation.

Transmission devices for general use in which variable speed controls are incorporated are well known and numerous types of transmissions of this general character have been adapted to perform special functions in the different arts. However, the heretofore known devices failed in various respects to satisfactorily solve the problems encountered in certain of the more exacting manufacturing processes and therefore in such manufacture, special mechanism had to be devised before specific problems could be overcome.

One specific problem that has been encountered in the spinning of artificial silk and which is present in other arts wherein a plurality of driven means are operated at speeds that must be changed a small degree during a relatively long period of operation is the provision of control means for changing the speeds of the driven means with the required precision.

It is an object of this invention to overcome the problem specifically mentioned above and to provide a mechanism wherein precision in gradation in speed of driven means may be accomplished in a simple and relatively inexpensive manner.

This invention contemplates a mechanism in which a plurality of driven means are each operated at different relative speeds from power sources operating at constant speeds and in which a common means is utilized for effecting a small percentage of relative speed change in each driven means.

Specifically in its relation to the art of producing artificial silk, this invention includes the provision of a mechanism in which succeeding portions of freshly formed plastic filaments are caused to be varyingly stretched during a complete spinning operation by being propelled over godets, the peripheral speeds of which are accurately modified to avoid the tendency of the artificial silk when dried normally in wound package form to have different affinity for dye

between the yarn constituting the inner convolutions of the package and the yarn constituting the outer convolutions of the package

A further object of this invention is the provision of a transmission mechanism for an artificial silk spinning apparatus by which the extruded filaments or yarn are caused to be stretched in the general manner and for the purposes well known in the art to a heretofore unattainable degree of accuracy. The mechanism specifically contemplated includes a planetary transmission for each godet or series of godets driven from the same shaft, and a single change speed unit connected to all of the planetary transmissions so that the movement of the epicycloidal gears of the respective transmission is controlled by this single change speed unit and so that a relatively large movement in the control unit is necessary in order to obtain relatively slight and hence accurate changes in the speeds of the respective godets.

Additionally, the present invention contemplates the driving of a godet of a rayon spinning machine, or other machinery which requires a very slow and small speed variation, in such manner that instead of the direct varying of the speed of the driven member by the utilization of one of the commercially available variable speed drives with resultant inaccuracies, the final speed is compounded by means of a form of differential gearing, in which one of the components is a constant one and the other component is derived from a variable speed unit thereby permitting utilization of a much larger variation range in the variable speed unit than is possible when the speed of the driven member is had by direct variation.

Other objects and advantages will be apparent from a consideration of the following detailed description when considered in connection with the accompanying drawings, wherein:

Figure 1 illustrates one form of the present invention which is shown for the purpose of exemplification incorporated in an apparatus for spinning artificial silk;

Figure 2 is a sectional view taken on line 2—2 of Figure 1;

Figure 3 is a detailed sectional view taken on line 3—3 of Figure 2; and

Figures 4 and 5 are detailed sectional views of a type of change speed mechanism which has been found particularly suited for utilization in the present complete transmission mechanisms.

In the complete spinning apparatus illustrated diagrammatically in Figure 1, a spinning or co-

regulating bath 10 is contained in a suitable receptacle 11 and a freshly formed filament or filaments 12 have been extruded into the bath through the spinneret 13. Filaments or yarn 12 are drawn from the bath and conducted to and around godet 14 and then to and around godet 15. After being passed over godet 15 the filaments are delivered to a collecting device 16 which is diagrammatically shown in the form 10 of a centrifugal pot.

While only one set of cooperating godets 14 and 15 have been illustrated in the drawings, it is to be understood that a plurality of sets of godets may be utilized depending upon the number of threads being spun, and that the transmission mechanism hereinafter referred to can be utilized to control the operation of many sets of similar godets, the speed of which has to be controlled in the same manner.

20 The detailed transmission mechanism for operating godets 14 and 15 is more fully illustrated in Figure 2 of the drawings and while this detailed mechanism is particularly adapted for use in a spinning apparatus as illustrated in Figure 1, 25 it is clear that it is also suitable for use in propelling any plurality of driven means wherein there is a cooperative relation between the driven means, and they are to be propelled at speeds which are changed in small degrees relative to 30 each other during a period of relatively long duration. For the purpose of this description, however, the driven means will be defined as godets.

A shaft 17, mounted for rotation in suitable 35 bearings and driven from a source of power (not shown), has a gear 18 fixed thereto, which gear meshes with gear 19 supported upon a shaft 20. Shaft 20 extends through a bearing 21 arranged in the upper portion of support 22 and it has 40 fixed to its end remote from gear 19 another gear 23. Gear 23 meshes with gear 24 and gear 24 is fixed to a shaft 25 which constitutes a part 45 of a planetary transmission designated generally as 26. A circular plate provided with an annular flange to form a dish-shaped enlargement on shaft 25 is designated by numeral 27 and an orbit or ring gear is internally arranged within the annular flange at 28. Shaft 25 is mounted in 50 bearings 29 arranged in a tubular extension 30 of a housing 31 which encloses and supports the planetary transmission.

The housing 31 is supported by means of a tubular extension 32 secured in a support 33. This extension contains bearings 34 in which is 55 mounted a tubular shaft 35 provided with a spider 36 at its inner end. Three epicycloidal planet pinions 37 are mounted upon the legs of the spider by means of shafts 38.

Godet wheel 14 is caused to be rotated by shaft 60 39 upon which it is carried, the shaft 39 extending through bearings 40 in tubular shaft 35. The end of shaft 39 is received in a journal 41 arranged in the base of the dish member 27. Between spider 36 and bearing 41 is a sun gear 42 65 which is keyed to shaft 39 and is in constant mesh with the epicycloidal planet pinions 37. Tubular shaft 35 is provided at its outer end with a spur wheel 43 which meshes with pinion 44 mounted upon a shaft 45, which shaft operates in 70 bearings 46 arranged in support 33.

A gear 47 is secured to the shaft 45 at its end opposite to pinion 44 and this gear 47 meshes with gear 48 which constitutes a part of a change speed mechanism 49. The change speed mechanism 49 may be of any of the well known com-

mercial types such as that shown, in which the speed change is preferably infinitely variable, that is, without step by step operation. In the particular type of change speed mechanism 49 illustrated, a housing 50 is provided which contains a shaft 51 mounted for rotation in bearings 52 and 53 contained in the side walls of the housing.

5 Shaft 51 has keyed thereto a sprocket wheel 54, or its equivalent, adapted to be driven from a suitable source of power (not shown) which is operated at a constant speed. Parallel to shaft 51 is another shaft 55. Shaft 55 is similarly mounted in the walls of the housing 50 of the change speed mechanism. Each of the shafts 51 and 55 has keyed thereto, but slidably mounted thereon, pairs of cones 56 and 57, respectively. A belt 58 is mounted so that its edges engage the cones on the respective shafts. Levers 59 which are pivoted at points 60, respectively, are attached to adjacent cones 56 and 57 and the levers are 10 adapted to be operatively pivoted in unison by means of a toggle 61. The movement of the levers causes the pair of cones 56 to be moved from each other and the pair of cones 57 to approach each other when they are pivoted in one direction and the opposite movement to be effected between the respective cones when the levers are moved in the opposite direction.

15 It will be seen that since it is the shaft 55 to which gear 48 is secured, the change speed mechanism, as a result of the constant speed of propulsion of the sprocket 54 will cause the shaft 55, and accordingly gear 48, to rotate at a speed which can be varied by moving the toggle 61 due to the fact that the relative speeds of the 20 shafts 55 and 56 will be modified by the adjustment of the respective cones with which belt 58 25 engages.

30 Toggle 61 may be automatically moved from the shaft on which it is mounted through the 35 medium of a reduction gear (not shown) which may be connected to a suitable source of power. It is preferable to drive the shaft of the toggle at a constant speed.

Another planetary transmission 62 is arranged 40 to drive the godet 15, the transmission being substantially identical with planetary transmission 26. Planetary transmission 62 is driven at a constant speed by shaft 63 from a source of power (not shown) and the power is transmitted to the 45 orbit gear 64 through the medium of reduction gears 65. A spider 66 carries the planet epicycloidal gears 67 which are meshed with orbit gear 62 and sun gear 68. The spider 66 is rotated by means of gear 69 which gear 69 is connected to 50 change speed mechanism 49 through the medium of an idler gear 70, a pinion 71, shaft 72, gear 73 and the gear 48.

55 In operation, if R represents the number of teeth on the orbit gear and S represents the 60 number of teeth on the sun gear, then the planet gears will have

$$\frac{R-S}{2}$$

65 teeth. Then if r and p represent the number of revolutions per minute made by the orbit gear and the spider that carries the planet gears, respectively, and s the revolutions per minute of the sun gear, then

$$s = p \frac{R+S}{S} - r \frac{R}{S}$$

70 p determines the variable component of the resultant speed and r the constant component in 75

the present arrangement and conditions can be chosen so that a large change in p will effect only a small change in s .

It is this principle which is utilized in the apparatus here involved and in the practicing of the present method. In the spinning of rayon yarn it is quite customary to gradually change the speeds of the respective godets, and these changes are relatively small and gradual during a period which may extend over several hours. In some instances when the initial speed of a godet is 200 revolutions per minute, the final speed is increased only to 205 revolutions per minute, under such circumstances. However, since the desired speeds of the godets and the variations in the speeds thereof during the spinning operations and the purposes of such modifications are well known in the art the various speeds of propulsion of the plastic filaments by the respective godets will not be specifically discussed. Furthermore, the pump speeds for causing extrusion of the solution into the spinning bath and the cooperating speeds of rotation of the respective godets together with the changes made in these speeds will not be specified as it will suffice to point out that by slight changes in the gear ratios and propulsion speeds of the driving shafts the present complete apparatus may be utilized to obtain the utmost accuracy in the production of artificial silk as well as in the production of other products requiring precision in speed changes of driven shafts.

To illustrate the applicability of the above general formula of the present invention, let us assume that the initial speed of a godet is 200 revolutions per minute which is supposed to increase during a period of several hours to 205 revolutions per minute. Now if the constant component

$$\frac{R}{S}$$

in the above general formula is chosen as 180 revolutions per minute, the variable component

$$\left(p \frac{R+S}{S} \right)$$

at the beginning of the period is 20 revolutions per minute and will have to increase to 25 revolutions per minute. Consequently, the variable speed mechanism by the intermediary of the differential gearing, is called upon to vary, in a ratio of 5 to 20 revolutions per minute or 25%, whereas, without the differential gearing the variable speed mechanism would be required to produce directly the speeds from 200 to 205 or only 2 1/2% increase. Thus the arrangement in this particular case increases the working range of the variable speed mechanism ten times, thereby making it far less susceptible to errors. Since means employed heretofore for effecting such small increases in speed have proved for the greater part unsatisfactory and unreliable, the problem of accurate control was present but the use of the epicyclic gear system and the control of the speed of the spider 36 which carries the planetary gears 37, permits a small percentage of change in the speed of the sun gear relative to that of the driving orbit gear to be effected by a large percentage change in the speed of the spider.

While the operation set forth has been described in connection with the planetary gear system for godet 15 the described operation is also applicable to the planetary gear system that drives the godet 14. However, in the operation

of the complete apparatus as illustrated in Figure 2, each transmission 26 and 62 is caused to be propelled in a manner so as to effect different speeds of rotation of the godets according to the particular spinning operation being utilized. The speed of the spider 36 through the sleeve 35 and the gears 43, 44, 47, and 48 can be controlled by the conventional speed change mechanism 49, which at the same time controls the speed of the spider 66 through the gear train 10 comprising the gears 48, 73, 71, 70, and 69. It will be noted that the last gear train recited includes an idler gear 70 which is adapted to drive the gear 69 in an opposite direction to that in which the gear 43 is driven. By properly selecting the gears for these two gear trains, it is possible to drive the spider 66 at such a speed that the sun gear 68 and the godet 15 that is secured to the same shaft can be made to rotate in the same direction as the sun gear 42 and the godet 14 that is driven by it. The gear trains can be selected in such a manner for given constant driving speeds on shafts 17 and 63 that the relative speeds of the godets 14 and 15 can be made to be in any desired proportion. Once established this relative speed will remain constant except for the small change effected by the superimposed variable speed originating from the variable speed mechanism 49. However, by changing this relative driving speed, considerable flexibility of the control of the relative godet speeds is attained.

It will be seen that by selecting a proper predetermined speed for each of the shafts 17 and 63 the godets 14 and 15 may be caused to be rotated at any desired respective speeds and that the speed of each may be changed through the medium of the change speed mechanism 49 so as to cause the speeds of the godets to decrease simultaneously, to increase simultaneously, or the speed of either one of the godets to be increased while the speed of the other is decreased.

What I claim is:

1. In a spinning apparatus for the production of artificial silk having a spinneret for extruding filaments, a draw-off godet for the newly formed filaments and a second godet for effecting a stretch in the newly formed filaments being propelled between the godets, a shaft for each godet, a planetary transmission for each godet comprising an epicyclic gear train, each epicyclic gear train consisting of a sun gear, a set of planet gears mounted on a rotatable support and meshing with the sun gear, and an orbit gear meshing with the planet gears, means for driving one part of the epicyclic gear train at a predetermined constant speed, a progressively changeable speed propulsion mechanism, means connecting the speed change mechanism to another part of the epicyclic gear train to thereby cause a compounded resultant speed change of each of the godets, said resultant speed change of each godet being in such a ratio as to cause the second godet to be propelled at a higher speed than the draw-off godet, thereby to effect a stretching of filaments being propelled between the godets.

2. In a spinning apparatus for the production of artificial silk provided with a spinneret for extruding filaments, a draw-off godet for the newly formed filaments, and a second godet for effecting a stretch in the newly formed filaments being propelled between the godets, a shaft for each godet, a planetary transmission for driving the draw-off godet shaft, a planetary transmis-

- sion for driving the second godet shaft, each of said transmissions having a sun gear, a set of planet gears meshing with the sun gear mounted upon a rotatable support for movement about the sun gear, and an orbit gear, means for driving the orbit gear of each transmission at a predetermined constant speed, a progressively changeable speed propulsion mechanism, means for connecting the change speed mechanism with the support for the planet gears of the transmission for driving the draw-off godet, and means for connecting the change speed mechanism with the support for the planet gears of the transmission for driving the second godet at a ratio to cause the second godet to be propelled at a higher speed than the draw-off godet, thereby to effect a stretching of the filaments being propelled between the godets.
3. In a spinning apparatus for the production of artificial silk provided with a spinneret for extruding filaments, a draw-off godet for the newly formed filaments and a second godet for effecting a stretch in the newly formed filaments being propelled between the godets, a shaft for each godet, a planetary transmission for driving the draw-off godet shaft, a planetary transmission for driving the second godet shaft, each of said transmissions having a sun gear fixed to its godet shaft with a set of planet gears meshing with the sun gear and mounted upon a rotatable support for movement about the sun gear, and an orbit gear, means for driving the orbit gear of each transmission at a predetermined constant speed, a progressively changeable speed propulsion mechanism, a gear keyed to the rotatable support for the planet gears of the transmission for the draw-off godet, reduction gearing connecting the changeable speed propulsion mechanism to said last mentioned gear, a gear key to the rotatable support for the planet gears of the transmission for the second godet, reduction gearing connecting the changeable speed propulsion mechanism to said last mentioned gear of the second godet transmission, the reduction gearing connecting the changeable speed propulsion mechanism to the transmission for said second godet including an idler gear for causing the rotatable support for the set of planet gears of said transmission to be driven in a direction opposite to the direction in which the rotatable

support of the transmission for the draw-off godet is driven, whereby a relatively large variation in the speed of the changeable speed propulsion mechanism may be utilized in connection with the constant speed orbit gear driving means of each transmission, to effect a slight degree of change in the respective speeds of rotation of the godets over a long period of operation.

4. Driving mechanism comprising a plurality of driven shafts, a planetary transmission for each shaft including a sun gear connected to the shaft, a spider carrying a set of planet gears meshing with the sun gear, an orbit gear meshing with the set of planet gears adapted to be operated at a constant speed and a gear by which the spider may be rotated, a change speed mechanism, the spider of each transmission through the medium of its said gear being connected to said change speed mechanism and being caused to be rotated thereby at a varied speed whereby when each of the orbit gears is operated at a constant speed, the movement of each spider with its respective set of planet gears will effect a variation in the speed of that shaft driven by the transmission which includes the respective planet gears.

5. Driving mechanism comprising a plurality of driven shafts, a planetary transmission for each shaft including a sun gear connected to the shaft, a spider carrying a set of planet gears meshing with the sun gear, an orbit gear meshing with the set of planet gears adapted to be operated at a constant speed and a gear secured to each spider for rotating the same, a reduction gearing assembly connected to the gear secured to one of the spiders, a reduction gearing assembly connected to the gear secured to another of the spiders, a change speed mechanism for driving both reduction gearing assemblies, the reduction gearing assemblies being of different ratio thereby to cause the movement of said spiders with their respective set of planet gears about their sun gears at different speeds so that when the orbit gears of the transmissions are operated at constant speeds modification of the speed of operation of the change speed mechanism will effect a different variation in the speeds of the respective driven shafts.

PETER P. KRIEK. 50
